United States Patent Office

Des. 185,111
Patented May 5, 1959

185,111

TELEPHONE ATTACHMENT

Dominick J. Yerace and Edward R. Murner,
Washington, Pa.

Application April 25, 1958, Serial No. 50,630

Term of patent 14 years

(Cl. D85—2)

We claim:

The ornamental design for a telephone attachment, as shown and described.
